Fig. 1.

Fig. 2.

Fig. 3.

Fig. 4.

FIG. 1 is a plan view of the boat embodying my new design,

FIG. 2 is a side elevational view taken from the side of FIG. 1, further illustrating my new design,

FIG. 3 is an elevational view taken from the front of the boat, further illustrating my new design, and

FIG. 4 is an elevational view taken from the rear of the boat in FIG. 1.

The characteristic features of my design reside in the combination wherein flanged gunwales project horizontally over an inset portion and medial opposed outwardly projecting portions of the hull have a configuration as best shown in FIGS. 3 and 4.

The ornamental design for a boat, substantially as shown and described.
